UNITED STATES PATENT OFFICE.

GEORGE W. GRANT, OF BUCYRUS, OHIO.

DESIGN FOR A TOP FOR DENTISTS' BRACKET-TABLES.

41,268.

Specification for Design.

Patented Mar. 28, 1911.

Application filed July 11, 1910. Serial No. 571,518. Term of patent 3½ years.

To all whom it may concern:

Be it known that I, GEORGE W. GRANT, a citizen of the United States, residing at Bucyrus, in the county of Crawford and State of Ohio, have invented a new, original, and ornamental Design for a Top for Dentists' Bracket-Tables, of which the following is a specification, reference being had to the accompanying drawing, forming part hereof.

Figure 1 is a top plan view, which consists of a corrugated edge and three raised

bars of equal distance from each other and from the two sides. Fig. 2, is a side view of the top showing the design of the corrugation. Fig. 3, is a bottom plan showing the design for the bottom.

I claim,

The ornamental design for a top for dentists' bracket tables, as shown and described.

GEORGE W. GRANT.
